UNITED STATES PATENT OFFICE.

ETTORE F. GIANNATTASIO, OF NEW YORK, N. Y.

INTERMITTENT SEARCH-LIGHT.

1,086,040.

Specification of Letters Patent.

Patented Feb. 3, 1914.

Application filed January 7, 1910. Serial No. 536,904.

To all whom it may concern:

Be it known that I, ETTORE F. GIANNATTASIO, of the city, county, and State of New York, have invented certain new and useful 5 Improvements in Intermittent Search-Lights, of which the following is a full description, reference being had therein to the accompanying drawings.

My invention relates to improvements in 10 intermittent search-lights, although the invention is applicable to other lamps where it is desirable to obtain a very powerful flash-light, without employing a supply of electric current, its main object is to produce an intermittent intense light for 15 signaling through thick fogs from vessels, locomotives and light-houses, without employing a supply of electric energy.

A further object of my invention is to 20 produce a lamp in which a flame derived from any source of gas supply is employed, and in which combustion is promoted by automatically conveying a combustible illuminant in the path of the flame.

Another object of my invention is to 25 produce a lamp of this character in which the mechanism is simple and easily operated.

Reference is to be had to the accompanying 30 drawings forming a part of this specification, in which similar reference characters indicate corresponding parts in all the views.

Figure 1 is a vertical sectional elevation 35 of the lamp illustrating my invention. Fig. 2 is a side elevation partly in section of the lamp, the view being taken at right angles to that shown in Fig. 1. Fig. 3 illustrates in detail the means for intermittently operating the receptacles which convey the combustible charges to the flame, and also means 40 for effectuating the distribution and agitation of the combustible as shown in Fig. 1. Fig. 4 is a partly sectional plan view of the lamp illustrating the flame which ignites 45 the combustible material, and Fig. 5 is a plan assembled view of the apparatus, showing the form of a casing used in connection with the lamp.

As illustrated in Figs. 1 and 2, the lamp 50 is provided with a suitable sub-base plate 10 containing grooves 11 and 12 for permitting the ball-bearings 0 to rotate freely, a plate 13 is secured to a base 14 by the bolts 55 15 and while the said plate 13 is resting on the ball-bearings the apparatus can be easily revolved laterally. The plate 13 is rev-

olubly mounted on the sub-base 10 and is held thereto by the flange 16^a of the pivot stud 16.

As shown in Fig. 2 a handle 17 is provided, 60 to enable the operator to flash a light in whichever direction he may choose, and by adjusting worm 18 toward stud 16 by means of a lever 19 the lamp can be set so, that the rays of light can be continuously directed 65 in a certain path.

The base 14 as sectionally illustrated in Fig. 1, is preferably hollow so that some mechanism can be contained within it.

The drawing shows a conventional electric motor 20, but I have not described its circuit because I claim nothing for it, as I do not limit the invention to any precise form of motor, however, any means of propulsion can be substituted for putting in 70 motion the gear 21, and I wish it understood that the intervals between the flashes are mainly determined by the speed of the said gear-wheel 21 therefore, any suitable induction coil or gearing can be applied to 75 the motor shown, so that the speed of the gear-wheel 22 can be reduced to about four revolutions per minute.

As the drawing shows, gear-wheel 22 is 80 driven by the motor 20 meshing with a mate 85 21, the latter having a depending shaft 23 on to which is secured a gear-wheel 24, said shaft 23 being supported by a bracket 23^a. To provide for an intermittent intense light, I use a combustible powder which is automatically conveyed in the path of the flame 90 25 and is ignited by the said flame, burning with a very powerful light. To produce the flame already referred to, I provide a tank 26 so that a supply of any compound which 95 develops gases may be contained within it, such as calcium carbide, the said gases being conveyed to outlet 27 through tubing 28.

To supply the charges of the combustible material, I provide a chamber 29 for holding same, and while I do not limit myself to the particular compound specified, I have found that an efficient compound of this kind is made of: sublimed sulfur 50%, bronze-powder 50%. In carrying out this 100 idea any suitable substance which will burn with a powerful light, and be ignited by the gas flame can be substituted.

The chamber 29 already referred to can 105 be placed at any convenient point on the 110 side of the lamp, and as the drawing shows the said chamber is supported on hood or

casing 30, and the latter is mounted on a housing 31. An agitator 32 is provided (see Fig. 1) which stirs the combustible powder and allows the same to fall on a revolving 5 piston or distributer 33, provided with a groove or slot and the said combustible material being of a very fine form, by its own gravity fills the said slot. This is effected each time the piston travels a full revolution 10 upward, and while at the downward rotation the combustible drops out and through outlet 34 it falls into a carrier comprising one or more receptacles 35. I have not described in detail the said distributer, because it is an old method and can be modified to meet various requirements, and I do not limit the invention to such construction. 15

As the drawing illustrates the receptacles 35 are clamped to arms 36 of the bracket 37 20 the latter being keyed on a shaft 38, the said receptacles can be made of any suitable material that will stand a high temperature, such as porcelain. In order to effect an intermittent rotation of the receptacles, and 25 to provide for a momentary stop of the same each time they are revolved to outlet 34, I provide suitable cams which I will now disclose. As plainly shown in Figs. 1 to 3 a gear-wheel 24 drives a gear 40 which is fastened on to a shaft 41, a cam 39^a is also secured to the said shaft, said cam meshing with a mate 39^b. Each of the cams is provided with four teeth, but should it be desired to have a less number of receptacles, 30 then in such a case the number of teeth in the said cams should be varied accordingly. The interval of rest of the receptacles referred to, can be best determined by the pitch and shape of the teeth 39^c and 39^d of 35 the said cams. The gear 40 which is secured on shaft 41, whenever it is put in motion, by the meshing of the cams, drives a gear-wheel 42 which is fastened on a shaft 38, and also drives a gear 42^a, a bevel-gear 42^b 40 is secured on to the said gear meshing with a bevel-gear 43 and the latter being secured to a shaft 44, which is supported by a bearing 45. As illustrated a pulley 46 is fastened on the shaft 44 and by means of a belt 47 connects with a pulley 48, the latter putting in motion the piston already referred to, and a pulley 49, is connected by means of a belt 50 with a pulley 51 which revolves the so called agitator 32, while a pulley 52 45 by means of a belt 53 rotates another pulley 54, which connects with another agitator partly shown.

As far as the invention is concerned, I do not confine myself to the connections 60 which I have just described, but however, if the said belts should be found to slip and to not effect a rotation of the mechanism already referred to, sprockets and endless chains can be easily substituted. The ratio 65 of the described gearing is, one to four, that

is: each time the bevel-gear 42^b is revolved a one-quarter of a revolution by the gear 42, bevel-gear 43 being a one-quarter of the size of the diametral-pitch of the said bevel-gear 42^b, it travels a one full revolution, thus effecting a full rotation of the distributer 33 and agitators. 70

To make the light more intense, I provide a reflector 55 behind the light, and a lens 56 in front of it, and as shown in Fig. 4, the flame 25 ignites the illuminant at the same time a receptacle is receiving a charge of the said compound. As illustrated in Fig. 5 a casing 30 is provided in which the light is formed, and in case there should be any 80 fumes or vapors, to allow the same to pass out quickly, I provide outlets 57^a and 57^b. 85

In the foregoing description I have referred to one form of mechanism embodying my invention, but I wish it understood that the mechanism which I have shown can be changed in many ways without departing from the principles of the invention. 90

Having thus fully described my invention, I claim as new and desire to secure by Letters Patent:—

1. In an intermittent searchlight, the combination with a gas flame, of a plurality of receptacles, a feed hopper having a combustible illuminant, means for holding said receptacles successively adjacent said feed hopper, means in connection with said feed hopper and independent of said receptacles for feeding a predetermined quantity of the illuminant to each receptacle and arranged 95 so as to prevent the escape of the illuminant from said holder when the receptacle is removed therefrom, said receptacles being arranged to present the illuminant contained therein to said gas flame. 100

2. In an intermittent searchlight the combination with a gas flame, of a plurality of receptacles, a bracket supporting said receptacles, means for revolving said bracket and receptacles, a reservoir for combustible illuminant arranged to supply a predetermined amount of the same to the receptacles, and means operatively connected with the bracket controlling the discharge of the illuminant into the said receptacles and 115 means for igniting the illuminant.

3. An apparatus of the kind described, comprising a set of cams, for revolving a plurality of receptacles intermittently, means for dropping predetermined charges 120 of a combustion material into the said receptacles, and means for igniting same.

4. An apparatus of the kind described, comprising cams for intermittently operating a plurality of receptacles connected to a 125 bracket, said cams also actuating a suitable gear drive, the latter operating a mechanism for supplying charges of a combustion compound to the receptacles, said receptacles conveying the material to the flame. 130

5. In an apparatus of the kind described, comprising a base resting on a sub-base plate, means for laterally revolving the same, a train of gears being connected to the base, revolving a cam, the latter meshing with a mate operating a plurality of receptacles in connection with a mechanism for controlling the distribution of a combustible illuminant, said illuminant being conveyed 10 into the path of a gas flame.

6. In an apparatus of the kind described, the combination of a sub-base plate, a base plate rotatably mounted on said sub-base

plate, means for rotating said base plate, a bracket rotatably mounted on said base plate 15 having a plurality of receptacles secured thereto, means for rotating said receptacles intermittently, means for supplying a combustible illuminant to said receptacles, a gas flame and means for rotating said receptacles into the path of said flame. 20
